UNITED STATES PATENT OFFICE.

COLIN F. HARDY, OF HARVARD, NEBRASKA.

DOUGH-RAISER.

1,249,620.

specification of Letters Patent. Patented Dec. 11, 1917.

Application filed March 20, 1916. Serial No. 85,432.

To all whom it may concern:

Be it known that I, COLIN F. HARDY, a citizen of the United States, residing at Harvard, in the county of Clay and State of

5 Nebraska, have invented certain new and useful Improvements in Dough-Raisers, of which the following is a specification, reference being had to the accompanying drawings.

10 This invention relates to certain improvements in dough raisers and it is an object of the invention to provide a device of this general character having novel and improved means whereby a heat insulating compartment is afforded which serves to retain for a prolonged period a moderate temperature within the device in order to facilitate the raising of the dough.

15 It is also an object of the invention to provide a device of this general character wherein a heat may be generated within the device and whereby the temperature within the device may be readily ascertained.

20 The invention consists in the details of construction and in the combination and arrangement of the several parts of my improved raiser whereby certain important advantages are attained and the device is rendered simpler, less expensive and otherwise 25 more convenient and advantageous for use, all as will be hereinafter more fully set forth.

25 The novel features of the invention will hereinafter be definitely claimed.

30 In order that my invention may be the better understood, I will now proceed to describe the same with reference to the accompanying drawings, wherein—

35 Figure 1 is a vertical sectional view taken through a dough raiser constructed in accordance with an embodiment of my invention, a portion of the electric heater being shown in section; and

40 Fig. 2 is a view in bottom plan of the cover as herein included.

45 As disclosed in the accompanying drawings, A comprises the base of my improved device which consists of a layer 1 of cardboard of predetermined dimensions and having imposed upon the central portion thereof the layers 2 of corrugated board, whereby a plurality of air cells are afforded, and as herein disclosed, the layers 2 are circular in form and adapted to be snugly fitted within the body portion B of my improved device as herein disclosed, said body portion

B being cylindrical in form and having the marginal portions of the layer 1 of cardboard overlying the lower wall thereof and suitably secured thereto whereby the base A 50 and the body portion B are permanently secured one to the other.

55 The body B also comprises a plurality of layers 3 of corrugated board whereby air cells are afforded, and the inner wall of the body portion B and the base A are provided with a lining 4 of asbestos and the outer faces thereof are covered with a layer 5 of strong paper fiber or canvas.

60 The removable top C is formed in a manner substantially identical to the base A except that the under faces thereof are provided with a covering 6 of felt or other compressible material so that an air-tight closure is assured when the top C is in applied 70 position. I also find it of advantage to provide the top C with a metallic plate 7 preferably of tin so that the handle member 8 may be effectively anchored in applied position.

65 The device as hereinbefore described results in a cabinet adapted to be of such dimensions as to have positioned therein a pan containing dough or the like, and it will be perceived that should the dough be made of 75 warm water and warm flour, the temperature of the dough or sponge will be maintained for a prolonged period of time after the top C has been applied. It will be particularly noted that by having the base A, 80 the body portion B and the top C including the superimposed layers of corrugated board, the resultant air cells afforded thereby renders the interior of the cabinet impervious to the atmospheric changes taking 85 place on the outside.

90 In the event that the dough or sponge is mixed from cold materials, a suitable heating medium may be initially applied within the cabinet such as the container 9 of predetermined height and adapted to fit snugly within the cabinet and upon which the dough containing pan P is adapted to be rested, said container being adapted to contain warm water or other liquid. It will 100 be perceived however that in lieu of the container 9, a heated soap-stone may be employed, as is well known.

105 However, for positively heating the interior of the cabinet, I prefer to employ the 110 electric heating element E carried by the under face of the top C and as herein dis-

closed, said element E consists of a winding 10 of fine wire around a flat piece of asbestos board 11, said winding 10 and the coating board 11 being positioned within the casing 19 of heat conductive material. The opposite ends of the wire 10 are electrically connected with a suitable source of electrical energy through the medium of the conductors a which extend through the insulated bushing 12 disposed through the top C at one side of the element E, as is believed to be clearly shown in the accompanying drawings.

The heating coil afforded by the wire 10 is covered with the asbestos sheets 14 and between the metallic plates 15, and said element E is held in operative position upon the under face of the top C through the medium of the straps 16, which are disposed 20 transversely of the heating element E adjacent the opposite ends thereof and across the inner and outer faces of the heating element. Headed bolts 17 are disposed through the closure member C and through the extremities 25 of the straps 16 and have in threaded engagement with the lower or inner ends thereof the nuts 18 which serve to clamp the heating element E between the straps 16 and to hold the heating element in applied position upon the closure member C. It is also 30 to be noted that the heads of the bolts 17 overlie the outer face of the closure member C.

I also find it of advantage to provide the 35 top C with a thermometer T, said thermometer being disposed through the top and having its bulb positioned therebelow, so that the same will be arranged within

the cabinet when the top C is in applied position.

From the foregoing description, it is thought to be obvious that a dough raiser constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

A dough raiser comprising a cabinet having an opening, a removable closure member for said opening and extending within the cabinet when in applied position, the portion of the closure member adapted to extend within the cabinet consisting of a plurality of laminations, an electric heater underlying the inner face of the closure member, plates overlying the heater, and removable bolts disposed through the laminations of the closure member and the plates whereby said heater is held in applied position and the laminations held against separation.

In testimony whereof I hereunto affix my signature in the presence of two witnesses.

COLIN F. HARDY.

Witnesses:

ELMER T. JEFFRIES,
ROY DE GROFF.
